Specification for Design.

Patented Apr. 18, 1922.

Application filed January 21, 1921. Serial No. 439,035. Term of patent 3½ years.

To all whom it may concern:

Be it known that I, GEORGE F. ADAMS, a citizen of the United States, residing at Omaha, in the county of Douglas and State of Nebraska, have invented a new, original, and ornamental Design for a Film-Reel Holder, of which the following is a specification, reference being had to the accompanying drawing, forming a part thereof.

The figure is a side view of a film reel holder, showing my new design.

I claim:

The ornamental design for a film reel holder, as shown.

In testimony whereof, I have affixed my signature in presence of two witnesses.

GEORGE F. ADAMS.

Witnesses:
